(57) CLAIM

The ornamental design for a garment as shown and described.

DESCRIPTION

FIG. 1 is a top front left perspective view of a garment showing my new design in an inverse state, wherein the inside of the garment when worn is presently shown as the outside of the garment;

FIG. 2 is a front view of the design shown of FIG. 1;

FIG. 3 is a rear view of the design shown of FIG. 1;

FIG. 4 is a left side view of the design shown of FIG. 1;

FIG. 5 is a right side view of the design shown of FIG. 1;

FIG. 6 is a top view of the design shown of FIG. 1; and,

FIG. 7 is a bottom view of the design shown of FIG. 1.

The break lines shown in the Figures indicate that the appearance of any portion of the article between the break lines forms no part of the claimed design. The broken lines in the Figures illustrate portions of the garment that form no part of the claimed design.
